CLAIM

The ornamental design for a photographic print washer, substantially as shown and described.

DESCRIPTION

FIG. 1 is a perspective front view of a photographic print washer, showing my new design;

FIG. 2 is a rear elevational view of the design of FIG. 1;

FIG. 3 is an end elevational view, taken from the right of the print washer as shown in FIG. 1;

FIG. 4 is an end elevational view taken from the left end of the print washer as shown in FIG. 1;

FIG. 5 is a top plan view of the design of FIG. 1; and

FIG. 6 is a bottom plan view of the design of FIG. 1. Hoses are fragmentarily shown in all views for ease of illustration and to indicate indeterminable length.

FIG. I
